UNITED STATES PATENT OFFICE

2,616,505

APPARATUS FOR EXTINGUISHING FIRES

Ehler Meyer, Jersey City, and Max Bassin,
Bayonne, N. J.

Application April 4, 1950, Serial No. 153,922

5 Claims. (Cl. 169—5)

1

This invention relates generally to the art of fighting fires and more particularly to an improved composition including carbon dioxide as a medium for extinguishing fires and to a method of and apparatus for employing such improved composition.

It is common practice to employ carbon dioxide in extinguishing fires but it is usually discharged from the container through a very narrow hose which results in a very short stream making it necessary for the fire fighter to approach close to the fire. This is dangerous and often times impossible owing to the intense heat. Furthermore, in order to be most effective the carbon dioxide discharge must be directed to the base or seat of combustion which is very difficult with such a short and narrow hose.

It is a prime object of the present invention to produce a composition including water and carbon dioxide that can be projected at a convenient and considerable distance from the fire yet effect a quick extinguishment of the fire and prevent a reflash or reignition thereof.

Another object of the invention is to provide an improved method of and apparatus for employing carbon dioxide as a fire extinguishing medium.

Another object of the invention is to produce a method and apparatus for projecting a stream including carbon dioxide a considerable distance while maintaining an entirely effective extinguishing concentration.

Another object of the invention is to produce a method and apparatus for projecting a stream including carbon dioxide a considerable distance while maintaining an entirely effective reignition preventing blanket over the area of direct application.

Another object of the invention is to provide a method and apparatus for effecting a discharge of water and carbon dioxide as a composite stream which will possess highly effective range and penetrating characteristics as well as a large field of application or area of coverage.

Another object of the invention is to provide an apparatus for employing carbon dioxide as a fire extinguishing medium that is simple in construction, economical to manufacture and highly efficient in use.

Other objects of the invention are to provide a composition for extinguishing fires that will create a fire extinguishing atmosphere around the fire, that will cool any highly flammable substance or material that is feeding the fire, and that will cut off from the fire zone, the vapors

2

that are rising from the flammable substance or material and mixing with air to form the combustible mixture.

The invention will be better understood from the description thereof to follow taken in connection with the accompanying drawings in which—

Figure 1 is a side elevational view of a system or apparatus embodying the invention, parts being broken away.

Figure 2 is a top plan view thereof.

Figure 3 is a vertical sectional view through the mixing tank showing the water inlet and composite discharge outlet thereof.

Figure 4 is a cross sectional view of the mixing tank showing the inlets for the carbon dioxide.

Referring to the drawings, an enclosed cylindrical pressure-tight tank or reservoir 1 is shown mounted on a platform 2 which may be part of a mobile truck, such as a fire engine, or may be part of a stationary structure. The tank has a horizontally disposed inlet pipe 3 for water which leads into the tank at its bottom end and has a horizontally disposed outlet pipe 4 at its top end for the mixture. The tank is filled with steel shavings 5 which are prevented from entering into the inlet 2 and outlet 3 by screens 6.

A number of high pressure cylinders 7 containing liquid carbon dioxide (CO₂) are disposed around the tank in spaced relation, three of such cylinders being shown. Each cylinder has a manually controlled valve 8 at its top or delivery side, which valve is connected by a flexible hose 9 to a coupling pipe 10 for connecting a pair of closely spaced inlet pipes 11 and 12. Each inlet pipe 11 is connected to a tapered nozzle 13 which projects through an internally screw-threaded opening 14 at the bottom end of the tank and is screw threaded in said opening. Each inlet pipe 12 is connected to a similar nozzle 15 projecting through an adjacent opening 16. Nozzle 13 is longer than its companion nozzle 15 so that it projects farther into the tank than the latter nozzle.

The water for the tank 1 is forced by a pump (not shown) through a supply hose or pipe 17. A sectioned pipe 18 connects supply pipe 17 and the tank inlet pipe 3 through connections 19 and 20, respectively. The water being pumped into the tank 1 may be previously treated for receiving the carbon dioxide by charging it with caustic soda or potash or other suitable chemical substance. For this purpose, an injector comprising a tank 21 for containing such substance is mounted on a coupling device 22 between the

aligned sections of pipe 18. The side wall of tank 21 has a downwardly extending tapered portion 23 terminating at its bottom end in a straight reduced neck portion having a discharge outlet. The neck portion seats on and is fastened in any suitable manner to an enlarged portion 24 of the top wall portion of the coupling device 22, its discharge outlet communicating with an inlet 25 formed in said enlarged portion. A key actuated valve 26 controls the discharge from tank 21 into the water in the coupling member 22. Water passes from pipe 18 through a tapered nozzle 27 extending into the coupling device to a point beyond the point of communication between the tank 21 and said coupling device. This causes a turbulence in the coupling device resulting in a thorough mixture of the water and substance from the tank 21.

In using the apparatus, the valves 8 of the cylinders 7 are manipulated and semi-liquid carbon dioxide is injected into the interior of the tank 1. The spaced and staggered relation of the nozzles 13 and 15 creates a turbulence or agitation of the carbon dioxide in the tank so that as the carbon dioxide passes upwardly it is uniformly distributed over the shavings throughout the tank in bubble formation, the bubbles clinging to the shavings. Water is pumped to the tank 1 under pressure and in passing through the supply pipe 18 is treated with the caustic soda or other substance from tank 21. The treated water in passing from the bottom to the top of the tank 1 through the steel shavings 5 readily picks up the carbon dioxide due to the bubble formation thereof. The caustic soda or other chemical from tank 21 present in the water prevents the carbon dioxide from expanding into gas. The mixture of water and carbon dioxide is carried through the discharge outlet 4 of tank 1 and through a vertically disposed pipe 28 connected at its top end to said outlet. From pipe 28 the mixture flows through a horizontally disposed pipe 29 connected at one end to the bottom end of pipe 28 and from pipe 29 to a fire hose 30 through connection 31. The fire hose has a nozzle (not shown) at its outer end for projecting the discharge on to the fire. An air compressor 32 is operatively connected in pipe 29 whereby the air is under slight compression when the pump is operating and the air forms an elastic cushion which prevents fluctuations or interruptions in the stream of the expelled liquid.

The combined water and carbon dioxide stream can be discharged through a hose of a width ordinarily used for discharging water and can be projected a considerable distance from the fire, the water serving to carry the carbon dioxide this distance.

It will be apparent that the field of application or area of coverage of the stream is very large and that the stream possesses highly effective range and penetrating characteristics.

The water keeps the carbon dioxide cool while being projected in the stream so that none of the carbon dioxide is lost due to expansion of heat. When the stream reaches the fire, the water absorbs the heat from the fire at the area of application and in so doing expands the carbon dioxide gas that is in solution in the water. The carbon dioxide will fall to the base or seat of the fire and will produce a wall or blanket at such point that will exclude oxygen and thereby smother the fire. The water also has a cooling effect on the material being consumed by the fire so that it is effective in preventing relight or re-

ignition and will permit the fire fighters to more closely approach the fire.

The proportion of carbon dioxide and water and the pressure of the water may be varied.

5 Utilizing cylinders of carbon dioxide of the type commonly used in fire extinguishing equipment and with a working water pressure of about 115 pounds in the tank 1, about 1% of carbon dioxide by weight is added to the water.

10 The presence of the carbon dioxide in the water permits a smaller amount of water to be used to extinguish the fire thereby reducing the chances of water damage.

15 The discharge also dispels the smoke and products of combustion quickly and penetrates rising air currents thereby permitting quick access to the fire resulting in the saving of time which is all important at a fire.

20 All types of fire are extinguishable by the present invention so that it is unnecessary when fighting a particular type of fire to lose time in hooking up an additional accessory when suddenly confronted with a different type of fire.

25 What we claim is:

1. A fire extinguishing system comprising an enclosed tank having steel shavings therein and having an inlet and an outlet, a source of supply of carbon dioxide under pressure in communication with the interior of the tank for depositing the carbon dioxide on said shavings, means for forcing a supply of water under pressure into the interior of and through said tank and through said shavings, a discharge pipe connected to said outlet, and means for directing the discharge from said discharge pipe on to a fire.

2. Apparatus for extinguishing a fire comprising, in combination, a tank containing metal shavings, said tank having an inlet and an outlet, a plurality of cylinders containing carbon dioxide under high pressure, pipes connecting said cylinders with the interior of the tank, nozzles on the ends of said pipes inside said tank for directing the carbon dioxide on said shavings, valve means on the cylinders for controlling the passage of carbon dioxide to the inside of the tank, a pipe for supplying water connected to said inlet and piping connected to said outlet for projecting the discharge on to a fire.

3. Apparatus for extinguishing a fire comprising, in combination, a tank containing metal shavings, said tank having an inlet and an outlet, a plurality of cylinders containing carbon dioxide under high pressure, pipes connecting said cylinders with the interior of the tank, nozzles on the ends of said pipes inside said tank for directing the carbon dioxide on said shavings, valve means on the cylinders for controlling the passage of carbon dioxide to the inside of the tank, a pipe for supplying water connected to said inlet, a device operatively connected to said water supply pipe for injecting a supply of caustic soda into the water supply and piping connected to said outlet for projecting the discharge on to a fire.

4. Apparatus for extinguishing a fire comprising, in combination, a tank containing metal shavings, said tank having an inlet and an outlet, a plurality of cylinders containing carbon dioxide under pressure, pipes connecting said cylinders with the interior of the tank, nozzles on the ends of said pipes inside said tank for directing the carbon dioxide on to said shavings, valve means on the cylinders for controlling the passage of carbon dioxide to the inside of the tank, means including a pipe connected to the inlet of the tank for conducting pumped water into said tank,

a device operatively connected to said latter pipe for injecting a supply of caustic soda into the water supply, piping connected to said outlet for projecting the discharge on to a fire and a device operatively connected to said piping for preventing fluctuations in the discharge.

5. Apparatus comprising, in combination, an elongated vertically disposed cylindrical pressure-tight tank packed with steel shavings, said tank having an inlet at its bottom end and an outlet at its top end, a plurality of cylinders containing carbon dioxide under pressure adjacent said tank, pipes connecting said cylinders with the interior of the tank, nozzles on the ends of said pipes inside said tank, said nozzles being arranged in offset and staggered relation to each other for directing the carbon dioxide throughout the shavings, valve means on the cylinders for controlling the passage of carbon dioxide into the tank, a horizontally disposed water supply pipe connected to said inlet for forcing water into and through

5

said tank and shavings outwardly of the outlet in the tank, and piping connected to said outlet in the tank for directing the mixture of carbon dioxide and water to a desired point.
